PREFABRICATED FENCE PANEL

John T. Hampton 834 Lori Ave., Sunnyvale, Calif.

Continuation of design applications Ser. Nos. 68,137 and
68,138, Jan. 2, 1962. This application June 8, 1962,
Ser. No. 70,684

Term of patent 14 years

(Cl. D28—1)

FIG. 1.

FIG. 2.

FIG. 3.

FIG. 4.

FIG. 6.

FIG. 5.

FIGURE 1 is a front elevational view of a prefabricated fence panel of one embodiment and embodying my new design;

FIGURE 2 is a rear elevational view of the embodiment of my prefabricated fence panel shown in FIGURE 1;

FIGURE 3 is a plan view of my prefabricated fence panel, as observed from the top of FIGURE 2;

FIGURE 4 is a front elevational view of a second embodiment of my prefabricated fence panel, embodying my new design;

FIGURE 5 is a rear elevational view of the embodiment of my prefabricated fence panel shown in FIGURE 4; and

FIGURE 6 is a plan view of the second embodiment of my prefabricated fence panel, as observed from the top of FIGURE 5.

This application is a continuation of my copending applications Serial Nos. D. 68,137 and D. 68,138, both filed January 2, 1962.

I claim:

The ornamental design for a prefabricated fence panel, substantially as shown and described.
